(57) **CLAIM**

The ornamental design for a wireless signal transmitter, as shown and described.

DESCRIPTION

FIG. 1 is a front perspective view of a wireless signal transmitter showing our design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view of another state of the wireless signal transmitter shown in FIG. 1.

The broken lines in the drawings depict environmental structure and boundaries only and form no part of the claimed designs to be patented.
